FRANK SACK AND FRANK A. TYLER, OF ST. MARY, NEBRASKA.

PIANO TUNING-PIN.

941,730.

Specification of Letters Patent. Patented Nov. 30, 1909.

Application filed September 15, 1908. Serial No. 453,108.

To all whom it may concern:

Be it known that we, FRANK SACK and FRANK A. TYLER, residing at St. Mary, in the county of Johnson and State of Nebraska, have invented a new and Improved 5 Piano Tuning-Pin, of which the following is a specification.

Our invention has for its object to provide an improved tuning pin for pianos, of a 10 simple and durable construction, and adapted for being conveniently applied for use and held locked from turning or working loose, and the said invention comprehends, generally, an improved form of tuning pin, 15 having its penetrating end split longitudinally and means operable from the outer or string receiving end for expanding the split end and holding the separated portions expanded, the said separated or split end members having their outer surfaces formed so 20 as to tightly bite into the wooden wrest plank or base into which the pins are driven.

In its more complete nature, our invention embodies a tubular piano tuning pin having 25 a string receiving head portion formed with a key engaging boss, a main threaded shank portion and a supplemental shank or penetrating end of less diameter than the main threaded shank portion, said end being split 30 longitudinally and having longitudinal external grooves and a coacting means adjustably mounted within the tubular pin and operable from the outer end of the pin for expanding the slotted penetrating end and 35 holding the same locked to the expanded position and to cause the said penetrating end to bite into the wood for preventing the pin from turning and working loose.

In its still more subordinate features this 40 invention consists in certain details of construction hereinafter fully described, specifically pointed out in the appended claims and illustrated in the accompanying drawing, in which:—

Figure 1 is a vertical section of our improved construction of tuning pin, the same being shown as driven into place, and the split end in normal shape. Fig. 2, is a similar view, and showing the locking and expanding means adjusted to expand the split ends to bite into the wood base. Fig. 3, is a perspective view that illustrates the pin in 50 position on the wrest plank and the string attached. Fig. 4, is a perspective view of the two parts that constitute the complete pin separated, and Fig. 5, is an enlarged detail

longitudinal section of the expanding end of the pin. Fig. 6 is a cross section on the line 6—6 of Fig. 5. Fig. 7 is a detail section showing another method of slitting the end 60 of the pin.

Our pin is more especially adapted for use on the usual types of wooden wrest plank members to which the pins are usually attached. The wrest planks are indicated by 65 the reference letter A in the drawings, and the plank A is reinforced as usual by the metal plate B. The metal plate B has the customary openings b to receive the wooden key receiving plugs as shown in Fig. 1. It 70 should be understood, however, that the arrangement of the wooden wrest plank member may be in any well known or approved manner, one end of the wrest plank A having the usual hitch pin g for holding one 75 end of the string.

The main shank portion 2 is of the usual length and of uniform diameter, except that portion below the string receiving space and the threaded portion. The body is so threaded that after the pin has been driven in and the tuning key applied, the said threads will screw into the wood and draw the pin positively into its bearing. The pin is also formed with a supplemental shank member 80 23 which is all of that part that extends from the threaded part, and the said shank member 23 is of a slightly reduced diameter so that after being driven home the lower 85 end of the pin as it enters or is driven into 90 the wood makes a socket of slightly less diameter than the threaded body or portion of the pin and thereby leaves sufficient surface on the walls of the socket in the wood for the threaded part of the pin to securely bite 95 into as the pin is forced home during the final turning during tuning.

Our tuning pin C consists of a tubular body having the usual key receiving head 1, a main shank portion 2, the upper end of 100 which terminates with an annular rim or shoulder 3 that forms the base for the key head 1 and which has an aperture 30 for receiving the end 40 of the string 4, the said shank portion having its upper end smooth 105 as at 20, that forms the winding or string drawing part of the pin.

The lower or supplemental shank member has its end made tapering or is of slightly conical shape to facilitate the driving thereof and the said end is slotted longitudinally 110 at one or more places as at 24, as clearly

shown in Figs. 1 and 2, by reference to which it will also be noticed that the bore α of the pin terminates some distance inside the penetrating end of the pin and at the end it is tapering or cone-shaped as at α' , the reason for which will presently appear. The outer surface of the supplemental shank portion is grooved longitudinally to form teeth or serrations 25.

10 D designates the locking and expanding means that forms a component part of our complete pin structure and the same comprises a long pin d , one end of which is tapering or cone shaped as at d' for engaging with the conical shaped portion α' of the split shank portion, the outer end having a screw neck d^2 and a screw head d^3 , the neck d^2 being provided to engage the internally threaded portion 26 of the bore α of the pin in the manner clearly shown in Figs. 1 and 2.

15 From the foregoing taken in connection with the drawing the complete arrangement of our pin and the advantages thereof will be readily apparent.

20 In applying the pin to the wrest plank A in the first instance, the same is driven in the usual manner, the shank end being in the usual position.

25 30 The string having been brought to the desired pitch, the screw pin D is then forced inwardly which causes the end of the said pin D to engage the conical surface α' and thereby cause the split end of the pin C to expand and bite into the wood, and since the grooves in the split end run lengthwise of the pin, the bite of the split end holds the pin from turning and the threads on the pin keep it from working outwardly, thereby 35 insuring a perfect locking of the pin to its tuned position.

40 When the string needs another tuning, the tuner first loosens the lock screw D to allow the split end of the pin to contract, to permit the pin to turn freely when applying the key. After the pin has been further turned to bring the string up to the desired tone, the lock or screw pin D is again tightened to expand the split end of the pin as before.

45 50 Having thus described our invention what we claim and desire to secure by Letters Patent, is:—

55 1. A tubular tuning pin for pianos, comprising a head and a main shank for receiving the string together with a supplemental or penetrating end, said end being longitudinally slotted to provide expansible portions, means for expanding said expansible portions, and means at the head of the 60 pin for operating said expanding means.

65 2. A tubular tuning pin for pianos, having a key receiving head, having an annular collar with a string receiving aperture, a main shank portion that receives the string, a supplemental or penetrating shank por-

tion, the latter being longitudinally slotted and an expander within the pin bore for engaging with the expanding or slotted end of the pin, said expander projecting through the head of the pin.

70

3. A tuning pin for pianos, comprising a tubular member having a head and a string receiving or main shank portion, and a supplemental shank portion, the latter being of less diameter than the main shank portion and being longitudinally slotted to form expansible members, and a means adjustable within the pin for expanding the slotted end of the pin.

75

4. A tubular piano tuning pin having a head portion formed with a collar having an aperture, a main shank portion for winding the string, said shank portion being externally screw threaded, a supplemental shank portion at the end of the threaded portion of less diameter than the threaded portion, said supplemental shank portion being slotted at the end, the bore of the supplemental shank portion being of less diameter than that of the main shank portion 80 and a screw plunger operable in the bore, having its penetrating end formed to engage the bore portion in the slotted end of the pin.

85

5. As a new article, a piano tuning pin comprising a tubular member having a key 90 receiving head portion, the bore of said portion being threaded, a main shank on which the string is wound, said main shank having an externally threaded surface, a main shank or penetrating end, of less diameter 95 than the main shank, said penetrating end being longitudinally slotted, the bore in said supplemental shank stopping short of the outer end and having a conical termination, combined with a screw plunger pin having 100 a threaded neck to engage the threaded portion of the bore, a conical end for engaging the conical termination of the bore, and a screw head, the slotted or penetrating end of the pin having longitudinally extended 105 grooves as set forth.

110

6. As a new article of manufacture, a piano tuning pin comprising a tubular member having a key-receiving head portion, a main shank on which the string is wound, 115 said main shank terminating in a slotted end to form expansible members, and means at the head of the pin and projecting through the pin to engage the expansible members to actuate the same.

120

7. A piano tuning pin comprising a hollow tubular member formed with a key receiving head portion at one end, and slotted at the other to form expansible members and an expander within the pin to engage said slotted end to actuate the same.

125

8. A piano tuning pin comprising a hollow tubular member formed with a key receiving head portion at one end and slotted at the other to form expansible members, an 130

expander within the pin to engage said slitted end to actuate the same, and means at the head of the pin to engage said expander for forcing the expander longitudinally when the expander is rotated.

5 9. A metal tuning pin threaded externally and having a central longitudinal slot whereby the pin presents opposite resilient

members, and means within the pin for expanding said resilient members.
